UNITED STATES PATENT OFFICE.

WILLIAM L. TILLOTSON, OF DENVER, COLORADO.

CURVED SCREEN FOR STATIONARY AND MOVING PICTURE REPRODUCTION AND MECHANISM FOR PRODUCING THE SAME.

1,089,448.

Specification of Letters Patent. Patented Mar. 10, 1914.

Application filed October 25, 1913. Serial No. 797,243.

To all whom it may concern:

Be it known that I, WILLIAM L. TILLOTSON, a citizen of the United States of America, residing in the city and county of Denver and State of Colorado, have invented a new and useful Curved Screen for Stationary and Moving Picture Reproduction and Mechanism for Producing the Same, of which the following is a specification.

10 This invention relates to improvements in curved screens for moving or stationary picture reproduction and mechanism for producing the same.

15 The object of the invention is to provide a screen support comprising resilient rods to which the upper and lower edges of the screen are attached, means being provided for bowing said rods whereby the surface of the screen is given a corresponding curvature, thereby to produce a cycloramic effect 20 in the reproduction of either stationary or moving pictures thrown thereon. Further, to provide parallel horizontally disposed resilient screen supporting rods, which are 25 hinged at one end to a fixed support, their opposite ends being threaded, said threaded ends being passed through swiveled abutment blocks and being provided with hand wheels which are in threaded engagement 30 therewith, the hubs of said hand wheels being extended so as to bear against the inner faces of the abutment blocks, whereby, when the wheels are turned in one direction, the rods are bowed in arcs of any desired curvature.

These objects are accomplished by the mechanism illustrated in the accompanying drawings, in which:

Figure 1 is a front elevation, illustrating 40 the screen and its supporting rods, and mechanism for bowing said rods with the screen, the stage front being shown partly in full and partly in dotted lines, and the screen presenting a flat surface. Fig. 2 is a 45 horizontal sectional view thereof, the rods with the screen being bowed; and Fig. 3 is a detail side view showing the manner of supporting the swiveled abutment blocks through which are loosely passed the threaded ends of the screen supporting rods.

In the scenic reproduction of photographs by means of the stereopticon, in either stationary or moving pictures, it is the common practice to throw the views upon a perfectly flat screen, but by so doing the best

results are not obtained, for while the figures in the screen are clearly reproduced, they appear flat and distorted to an extent to mar the general effect of the view. In 50 order to overcome this objection and to produce views in which the relief effect is uniform throughout the width of the screen, I employ a curved screen, and means for varying the curvature of the arc of the said screen relatively to the dimensions of the 55 hall or room in which it is placed, thereby to produce the best results, the curved surface of the screen giving to the pictures thrown thereon an effect similar to that produced by the curved picture surface in the well-known cyclorama.

Referring to the accompanying drawings: The numeral 1 indicates a stage front of any preferred style, comprising a platform, and side and top members which form the surrounding frame work for the opening back of which the picture screen is supported. Back of this frame work and on either side of the opening formed thereby, are rigidly secured suitable uprights 2 and 3. To the 60 upright 2, at points corresponding to the upper and lower edges of the picture screen, are hinged at one end resilient rods 4 and 5. At corresponding points on the upright 3, are secured brackets 6 and 7, having forked 65 or bifurcated portions in which are pivotally mounted blocks 8 and 9, the axes of which are vertical. The blocks are provided with horizontally disposed apertures, through which are passed the free ends of 70 the rods 4 and 5. These ends of the rods are threaded for a considerable distance from their extremities, and they extend a suitable distance beyond the outer faces of 75 the blocks, but the holes in the blocks are smooth and large enough to allow the rods to pass loosely through them. Upon the threaded portions of the rods are mounted hand wheels 10 and 11, respectively, the hubs 80 of which are threaded to engage the threaded portions of said rods. These hubs are slightly extended, as shown, and bear against the inner faces of the blocks 8 and 9 respectively. Upon the rods 3 and 4 are secured the upper and lower edges of an ordinary 85 screen 12, the four edges of the screen, together with the uprights, the hand wheels and swivel blocks, being hidden from view by the frame work of the stage front.

When it is desired to bow the rods to 90

curve the surface of the screen, the hand wheels are turned to cause their hubs to bear against the swiveled blocks, and as the wheels move forward on the rods, the rods 5 are at the same time drawn backward through the holes in the blocks, and as the opposite ends of the rods are held by their hinge connection to the upright 2, the result is a bowing or curving of the rods.

10 The hinge connection at one end of the rods and the swiveled blocks, through which their opposite ends pass, causes the rods to bend on a horizontal plane, and the blocks turn as the rods bend, so that their inner 15 faces always lie parallel with the faces of the hubs of the hand wheels. By this arrangement, the screen can be curved and maintained in an arc of any practicable radius, so that the best results may be obtained under varying conditions.

20 Having described my invention, what I claim as new and desire to secure by Letters Patent, is:

1. In a device of the character described, 25 the combination with supports, of rods secured to said supports, a picture screen on said rods, and means for bowing said rods.

2. In a device of the character described, 30 the combination with parallel supports, of parallel rods secured to said supports, a picture screen secured to said rods, and means for adjustably bowing said rods.

3. In a device of the character described, 35 the combination with parallel uprights, of horizontally disposed parallel rods hinged at one end to one of said uprights, automatically adjustable abutments on the opposite upright, through which the free ends of the said rods pass, hand wheels threaded 40 to said rods and in engagement with said abutments, and a picture screen supported upon said rods.

4. In a device of the character described, 45 the combination with supports, of horizontally disposed parallel resilient rods hinged at one end to one of said supports, swiveled

abutment blocks mounted on the other support having horizontally disposed bearing apertures, the free ends of said rods being threaded and supported loosely in said bearing apertures, a picture screen secured at its upper and lower ends to said rods, and means for bowing said rods, comprising hand wheels threaded thereon, the hubs of which bear against the inner faces of said 55 swivel blocks.

5. In a device of the character described, the combination with a support, of horizontally disposed parallel resilient rods hinged at one end to said support, a second support, 60 brackets thereon, swivel blocks mounted in said brackets having horizontal bearing apertures, the free ends of said rods being threaded and passed loosely through said bearing apertures and extended beyond 65 said blocks, hand wheels threaded to said rods, having elongated hubs which bear against the inner faces of said blocks, and a picture screen secured at its upper and lower ends to said rods, said rods, with the 70 screen, being bowed by screwing the said hand wheels against the said swiveled blocks.

6. In a device of the character described, the combination with supports having a 75 picture screen secured thereto, of means for bowing said supports in an arc of a required radius, and for maintaining said arcs.

7. In a device of the character described, 80 the combination with parallel rods fixed at one end, of supports in which the opposite ends of the rods are loosely mounted, means engaging said rods and in bearing contact with said supports for drawing said rods through said supports, thereby to bow them 85 and to maintain them in bowed relation.

In testimony whereof I affix my signature in presence of two witnesses.

WILLIAM L. TILLOTSON.
